UNITED STATES PATENT OFFICE.

SILAS HAWKINS, OF LOS ANGELES, CALIFORNIA.

TENT.

Application filed July 3, 1923. Serial No. 649,248.

To all whom it may concern:

Be it known that I, SILAS HAWKINS, a subject of the King of Great Britain, residing at Los Angeles, in the county of Los Angeles 5 and State of California, have invented new and useful Improvements in Tents, of which the following is a specification.

This invention relates to tents, and more particularly to tent frames.

10 An object of the invention is to provide a knock-down tent frame composed of tubular and telescopic elements that are adapted to be compactly telescoped one within the other so that all of the frame sections, when 15 mutually telescoped, may be packed in a comparatively small space to facilitate transportation and storage, especially for vehicular touring parties. An object is to provide a sectional tent skeleton or framework in 20 which the various elements are adapted to be assembled when complementary sections are extended one on the other, and an object is to provide means for securely fastening the assembled and erected skeleton or frame 25 sections to obtain a rigid framework.

Another object is to provide a tent structure including a rigid framework upon which the tent walls and roof members are 30 adapted to be readily mounted and dismounted, and further, to provide means for permitting the natural variation of dimensions of the tent fabrics according to expansion and contraction of the same without lacerating the tent fabrics and without dis- 35 torting the frame members.

Other objects and advantages will be made manifest in the following specification of an embodiment of the invention illustrated in the accompanying drawings, wherein:

40 Figure 1 is a perspective of the erected tent.

Fig. 2 is a vertical, longitudinal section of the erected tent.

Fig. 3 is a vertical, transverse section on line 3—3 of Figure 2.

Fig. 4 is a vertical section on line 4—4 of Figure 2.

Fig. 5 is a perspective of the erected tent skeleton.

50 Fig. 6 is a sectional detail showing fastened telescopic tubes.

Fig. 7 is a detail of the tent pole top joint.

Fig. 8 shows a modified form of frame element in which the tube is of rectangular 55 cross section.

The invention consists of a tent frame

including poles preferably of telescopic tubes including foot sections 2, intermediate sections 3 telescoping in the foot sections, and top sections 4 telescoping in the intermediate sections and having upper ends cut obliquely as at 5, Figure 7, so that contiguous ends of top sections 4 can be abutted end to end and secured firmly together. The upper ends of the top sections 4 are adapted 60 to be enclosed in a fork 6 having an upwardly extending shank 7. Through the arms of the fork 6 and the abutted ends 5 of the top sections 4 is passed a fastening key 8.

The fastening keys, of which a number are used for fastening the various elements of the tent skeleton, are preferably provided with an eye 9 at one end and are apertured at the opposite end to receive a pin 10 70 whereby the key is prevented from being accidentally dislodged or pulled from the sections through which it may be passed to secure the sections in attached position, as in Figure 6. The pin 10 is preferably permanently attached to the fastening key 8 as by means of a piece of string or other flexible medium 11.

The telescoping ends of the several pole sections are adapted to be adjusted so that 85 apertures therein will be registered to receive the respective fastening keys 8, which will therefore hold the pole sections in extended position. The pole sections are adapted to be telescoped one within the 90 other when the frame is knocked down so as to obtain a compact nesting of the various elements.

A ridge member consists of tubular or other sections 13 within the abutted end 95 portions of which is a core or supporting tube 14, Figure 2, which is provided with apertures 15 to be registered with apertures in the abutting ends of the ridge sections 13 and receive fastening pins 16, thus rigidly 100 connecting and supporting the inner abutted ends of the ridge tube sections 13. The outer ends of the ridge tube sections are perforated at 17 to receive the upwardly extending shanks of the apex or crotch or fork 105 piece 6.

Mounted around the shanks 7 are compressible springs 18, on which the ridge pole rests yielding so that when the tent top T is applied, as in Figure 1, and secured to the frame, the fabric can shrink and expand 110 with yielding action of the ridge pole and

thus prevent mutilation of the top fabric or distortion of the frame parts.

The sectional tent poles form inverted V's when assembled and to transversely brace the legs or posts, and further, to provide supports for the curtain wall W, transverse members consisting of tubes 20 are provided, and these are perforated at 21 to provide for the reception of the topmost post sections 4. The transverse tubular members 20 are also perforated at 22 to provide for reception of end pieces 23 of a longitudinal central brace 24 which is made of similar tubular sections, as clearly shown in Figure 2.

In the abutted ends of the sections forming the central brace 24 is a telescopic core or plug 25, through which passes a fastening key 26 similar to the key 8 previously described. This key fastens a section of the brace 24 to the core member 25 in a detachable manner. An intermediate transverse brace is provided and consists of similar sections 27, one of which is provided with a core portion 28 telescoping in the opposite aligned section 27. These members are secured by a fastening key 29, Figure 5. The central transverse brace device 27 is supported in one of the sections of the longitudinal brace 24, which latter is perforated as in Figure 4 to receive the core or stem portion 28. The sections 27 of the intermediate transverse brace abut against the opposite sides of the brace member 24, as shown in Figure 4. The transverse devices 20 and 24 have reduced end portions 30 and have shoulders 31. The tent wall W, which is preferably made of one piece, is adapted to be hung on the reduced portions 30 of the several transverse members.

Preferably, the top edge of the marginal portion of the wall W is provided with eyelets or grommets 32, Figure 3, to slip over the reduced portions 30 of the transverse members and to fit against the shoulders 31 thereof so as to hold the tent wall in suspended and definitely spaced position around the frame, as clearly seen in Figures 1, 2 and 3. The lower portions of the panels 50 of the walls W are yieldingly attached to the lower sections 2 of the tent frame as by means for springs 33 connected to the wall fabric and having hooks 34 at their lower ends to enter apertures 35 provided therefor in the lower sections of the upright legs or poles. This yieldable connection serves to draw the tent panels taut and at the same time allows them to shrink or expand without laceration of the fabric or injury to the frame.

The meeting ends of the wall may be overlapped, as clearly shown in Figure 1, to form the front opening and closure of the tent.

The top T is provided with grommeted openings 32, Figure 1, to pass over the reduced

retaining parts 30 of the transverse frame members; the top being provided with pendant flanges of eave-forming portions E.

Obviously, the tubular telescopic members that are adapted to be fitted and telescoped one within the other may be of circular or other cross section. Telescopic members of rectangular cross section are shown in Figure 8. This form of tube has the advantage of always presenting the respective apertures in the sections with proper sides in constant register, since the telescopic sections cannot rotate and thus turn the apertures out of respective position.

From the above it will be seen that I have provided a tent skeleton or frame consisting of tubular elements including complementary parts which are adapted to be readily compactly telescoped to occupy small space when knocked down and which are capable of being quickly extended in the erection of the frame and effectively secured against accidental dislocation when the tent frame is set up. At the same time, I have provided a tent frame which is of rigid structure when erected and which, being of tubular material, may be of minimum weight and yet retain the desired strength of parts.

Further embodiments, modifications and variations may be resorted to within the principle of the invention.

What is claimed is:

1. A tent structure comprising, in combination, a skeleton frame of tubular telescopic and extensible upright and telescopic and extensible transverse members, a fabric wall adapted to be suspended upon the transverse members of the frame, and a fabric top adapted to be mounted upon the frame and having portions overlapping and forming eaves around the top of the wall, the skeleton including a tubular knock-down yieldably mounted ridge pole adapted to move upon contraction and expansion of the tent top to protect the same against laceration.

2. A tent structure comprising, in combination, a skeleton frame of tubular telescopic and extensible upright and telescopic and extensible transverse members, a fabric wall adapted to be suspended upon the transverse members of the frame, a fabric top adapted to be mounted upon the frame and having portions overlapping and forming eaves around the top of the wall, and means for yieldingly attaching the tent wall to the frame so as to provide for expansion and contraction of the tent wall without laceration thereof and injury to the frame.

3. In a tent structure, a skeleton frame including a pair of convergent end poles at each end of the frame, a ridge pole mounted upon the convergent ends of the end poles, transverse end brace members mounted on the convergent end poles, and a longitudinal

brace member mounted with its ends extending through the transverse end braces of the frame.

4. In a tent structure, a skeleton frame including a pair of convergent end poles at each end of the frame, a ridge pole mounted upon the convergent ends of the end poles, transverse end brace members mounted on the convergent end poles, and a longitudinal brace member mounted with its ends extending through the transverse end braces of the frame, the ends of the transverse braces being provided with portions forming supports upon which a curtain wall may be suspended.

5. In a tent structure, a skeleton frame including a pair of convergent end poles at each end of the frame, a ridge pole mounted upon the convergent ends of the end poles, transverse end brace members mounted on the convergent end poles, and a longi-

tudinal brace member mounted with its ends extending through the transverse end braces of the frame, the ends of the transverse braces being provided with reduced portions 25 forming supports upon which a curtain wall may be suspended.

6. In a tent structure, a skeleton frame including sectional poles arranged in pairs each including convergent poles, means for 30 fastening the contiguous convergent ends of each pair of poles, and said means including shank portions, a ridge pole adapted to be mounted upon the said shank portions, and yielding means on said shank portions and 35 upon which the said ridge pole is yieldingly mounted so as to move in accordance with expansion and contraction of an applied tent top.

In testimony whereof I have signed my 40 name to this specification.

SILAS HAWKINS.
